CLAIM

The ornamental design for a combined dual brush and comb device, as shown and described.

DESCRIPTION

FIG. 1 is a front perspective view of a combined dual brush and comb device.

FIG. 2 is a rear perspective view of the combined dual brush and comb device of FIG. 1.

FIG. 3 is front elevational view of the combined dual brush and comb device of FIG. 1.

FIG. 4 is a rear elevational view of the combined dual brush and comb device of FIG. 1.

FIG. 5 is a left-side elevational view of the combined dual brush and comb device of FIG. 1.

FIG. 6 is a right-side elevational view of the combined dual brush and comb device of FIG. 1.

FIG. 7 is a top plan view of the combined dual brush and comb device of FIG. 1; and,

FIG. 8 is a bottom plan view of the combined dual brush and comb device of FIG. 1.

Broken lines in the figures show features that form no part of the claimed design.

1 Claim, 6 Drawing Sheets
